US00D774502S

(12) **United States Design Patent** (10) Patent No.: **US D774,502 S**
Cho et al. (45) Date of Patent: **** Dec. 20, 2016**

(54) **BUTTON SET FOR AN ELECTRONIC DEVICE**

(71) Applicant: **Creative Technology Ltd**, Singapore (SG)

(72) Inventors: **Mei San Gigi Cho**, Singapore (SG); **Huang Pheng Vince Ang**, Singapore (SG)

(73) Assignee: **Creative Technology Ltd**, Singapore (SG)

(**) Term: **14 Years**

(21) Appl. No.: **29/495,538**

(22) Filed: **Jul. 1, 2014**

(30) **Foreign Application Priority Data**

Jan. 3, 2014 (SG) D2014/5/B

(51) **LOC (10) Cl.** **14-03**

(52) **U.S. Cl.** **D14/257**
USPC .....

(57) **CLAIM**

The ornamental design for a button set for an electronic device, substantially as shown and described.

DESCRIPTION

The sole FIGURE is a front view of a button set for an electronic device showing our new design.

The broken line(s) define the bounds of the claimed design and form no part thereof.

1 Claim, 1 Drawing Sheet
